W. E. WINE,
CAR DOOR LOCKING HOOK,
APPLICATION FILED JAN. 10, 1922.

1,431,501.

Patented Oct. 10, 1922.

Inventor:

William E. Wine,
by Parker Cook,
Atty.

UNITED STATES PATENT OFFICE.

WILLIAM E. WINE, OF TOLEDO, OHIO.

CAR-DOOR-LOCKING HOOK.

Application filed January 10, 1922. Serial No. 528,249.

To all whom it may concern:

Be it known that I, WILLIAM E. WINE, a citizen of the United States of America, residing at Toledo, in the county of Lucas and State of Ohio, have invented certain new and useful Improvements in Car-Door-Locking Hooks, of which the following is a specification.

My invention relates to new and useful improvements in hooks and especially to hooks that are designed for supporting and holding the drop doors of freight cars, although, of course the hooks about to be described may be used equally as well with

drop or swinging doors of any description. One of the objects of the present invention is to provide a hook which will be exceedingly strong, relatively light in weight, and having a main supporting ledge that is widened on the outer surface of the hook to provide a greater bearing surface. Also to provide a supplemental or auxiliary ledge which may be used either to support a door before the same is forced or pried to its final resting position on the main supporting ledge; or which ledge may serve as a fulcrum for a stick or bar to release the hook from the door or as a fulcrum for a bar that may be extended to an oppositely positioned door so that it may be lifted to its final resting place on a main supporting ledge of another hook.

Still another object of the invention is to provide a hook with a supporting ledge, which is widened to present a maximum supporting surface and to form on the hook an extension which will provide a second or auxiliary ledge and said hook having ribs extending from the point of the hook and from the point of the extension rearwardly to merge into a rear outstanding wall, which wall will present a receptive striking surface that may be hit with a hammer or wrench, which will quickly release the hook from its supporting position.

Still another object of the invention is to provide a hook of the character described that will be exceedingly strong, relatively light in weight, neat in appearance and relatively cheap to manufacture.

With these and other objects in view, the invention consists in certain new and novel constructions as will be hereinafter more

fully described and pointed out in the claims.

Referring to the drawings, showing a preferred embodiment of the invention,

Fig. 1 is a side elevation of the invention, the dotted lines showing an angle iron of a door in a supported position and a bar resting on the auxiliary supporting ledge for prying the hook from the door.

Fig. 2 is a front edge view of the hook showing the widened supporting ledge and the outstanding wall formed at the lower end of the hook.

Referring now more in detail to the two figures there is shown a hook 1 which is substantially of eye-beam construction: it being preferably cast with the web 2, and the outer front and rear ribs or flanges 3, which at their upper ends merge into the boss 4 having a circular opening 5 formed therein.

A main flat supporting ledge 6 is shown extending out to the point of the hook 7, the front flange 3 then extending rearwardly, and merging with the rear outer flange of the hook.

This main supporting ledge is widened as at 8 by increasing the width of the flange as clearly shown in Fig. 2 so that the supporting surface of the ledge will be greater than the mean width of the hook.

This flange, which is diverted from its general direction to form the supporting ledge, may be extended out to either side of the web, but it is generally desirable to arrange it with its major portion to the outer side of the web of the hook rather than to the inner side thereof, as the housing with which such hooks are generally used may then be constructed in a more economical manner. In some cases, however, the major portion of the supporting ledges might be definitely arranged with respect to the web 2.

This is desirable in a hook of this character, as has heretofore been mentioned, the hook is designed to be used primarily for the support of drop car doors, which doors are generally provided with an angle iron which forms the bearing surface that rests on the supporting ledge of the hook, and although these angle irons extend out beyond the edge of the door for a short distance to rest on the hooks it is desirable to have as wide a

Having thus described the same, what I claim and desire to secure by Letters Patent is:

1. A hook having its shank of a webbed section with flanges outstanding from the web, one of the flanges being diverted to form a supporting ledge, the diverted portion of the flange being disposed mainly to one side of the web. 70

2. A hook having two supporting ledges, one of said ledges being widened and to one side only of the median line of the hook. 75

3. A hook having two supporting ledges, the upper of which is widened to present a greater bearing surface than the median width of the hook, and the one side of said hook presenting a relative unbroken surface. 80

4. A hook having a supporting ledge, said ledge being widened, a supplemental portion formed on the lower end of the hook providing a second supporting ledge and said supplemental portion being enlarged at its rear to form an outstanding wall or lug. 85

5. A hook comprising a shank and a supporting ledge, said supporting ledge being enlarged, an auxiliary portion formed on the lower end of the hook, the forward end of which forms a supplemental supporting ledge and the rear of which is enlarged to form a wall, said wall formed on the outer surface of said hook. 95

6. A hook comprising a relatively flat shank and supporting ledge, said ledge being widened on the outer side of said shank, a depending portion formed on the hook and a second supporting ledge formed therein, the depending portion being enlarged to form a wall and said wall being deposited on the outer surface of said hook. 100

7. A hook comprising a relatively flat shank, a supporting ledge, the ledge widening out on one side, an auxiliary integral depending portion having a supporting ledge, ribs extending rearwardly of this portion merging in a wall, and the wall extending outwardly from the outer surface of said shank to form a receptive striking means. 110

8. A hook of substantial I-beam section, the supporting ledge being flared on the outer side of the hook, a rib extending from the ledge to the rear rib of the hook, a depending portion below said rib and an auxiliary ledge formed in said portion, a second rib extending to the rear rib, both of said ribs merging in a wall and said wall being at right angles to the body portion of the hook and forming a receptive striking surface. 115

In testimony whereof I affix my signature.

WILLIAM E. WINE.

supporting ledge on the hook as possible as here is bound to be some lateral motion of the hook and slight shifting of the doors due to the movement of the car, and the greater the bearing surfaces, the less chance for the hook to become disengaged from the angle.

Below the rearward extending portion of the rib 3 there is a further rib 9 which extends downwardly and outwardly to form an auxiliary supporting ledge 10, the rib 9 then extending rearwardly as at 11 and merging with the wall 12 that is formed at the lower rear end of the hook. This wall 12 formed at right angles to the web 2 of the hook merges at its top as at 13 with the rear web 3 and is reinforced by merging with the portion 11 of the rib 9 and the rearwardly extending portion of the rib 3.

It is to be noticed that the widened portion 8 of the supporting ledge 6 and the outstanding wall 12 are both placed on the outer side of the hook as the inner side should present a substantially flat or plain surface as this surface will be adjacent the side of the car body.

From the foregoing it will be seen that I have provided a hook that is relatively strong and relatively narrow, and light in weight, the main supporting ledge of which however, is substantially widened to represent a maximum bearing surface. Furthermore, a second supporting ledge is provided which may support the door so that the same may be conveniently pried to its final position on the main supporting ledge or which auxiliary ledge may be used as a fulcrum for lifting an adjacent door to its final position, or may be used as a fulcrum to release the hook from contacting with the door.

Again, a rear striking wall is provided so that when desired to quickly release the hook from the door it is only necessary to hit or strike this which will swing the hook free.

5. It is to be remembered that in coal cars the weight on the doors is very great and that arrangements as above described are necessary because the hook cannot be simply grasped by the hand and pulled back to release the doors.

It will also be understood that although the hooks as described are to be primarily used with hopper car doors or gondola car doors, they may be used on any doors of 55 drop bottom type.

In the present invention I have shown the hook as formed of I-beam construction, but other sections might be used, and further ribs provided to strengthen the hook, if found necessary.

Many slight changes may be made without in any way departing from the spirit and scope of the invention.
